CLAIM

The ornamental design for a go kart as shown and described.

DESCRIPTION

FIG. 1 is a front perspective view of the go kart showing my new design;

FIG. 2 is a rear perspective view thereof;

FIG. 3 is a top perspective view thereof;

FIG. 4 is a left side elevational view thereof;

FIG. 5 is a right side elevational view thereof;

FIG. 6 is a front elevational view thereof;

FIG. 7 is a rear elevational view thereof;

FIG. 8 is a bottom plan view thereof; and,

FIG. 9 is a top plan view thereof.

The broken lines shown in the figures are for the purpose of illustrating portions of the go kart, which form no part of the claimed design.
